UNITED STATES PATENT OFFICE

GERALD DEAKIN, OF NEW YORK, N. Y., AND LIPA POLINKOWSKY, DECEASED, LATE OF PARIS, FRANCE, BY EDOUARD FRUM, ADMINISTRATOR, OF PARIS, FRANCE, ASSIGNEES TO INTERNATIONAL STANDARD ELECTRIC CORPORATION, OF NEW YORK, N. Y.

TESTING ARRANGEMENT FOR AUTOMATIC OR SEMIAUTOMATIC TELEPHONE SYSTEMS

Application filed May 13, 1930, Serial No. 452,085, and in Great Britain May 14, 1929.

The present invention relates to automatic or semi-automatic telephone systems and is more particularly concerned with arrangements for effecting routine tests of apparatus used therein. Such tests consist in periodically operating such apparatus in the same way as would occur if it were being used in the setting up of ordinary connections.

An object of the invention is the provision of a simple and efficient arrangement for testing the switching apparatus in an exchange of the kind in which the conversation selector switches are operated under the control of control circuits each common to a plurality of conversation switches but individual to a particular switching stage.

According to one feature of the invention in an exchange of this kind, a testing arrangement is provided which is adapted to be associated automatically in turn with each of a plurality of conversation switches and to perform automatically a series of operations similar to those operations which would occur in an ordinary connection whereby the operation of each of said conversation switches in conjunction with an associated control circuit is tested.

In accordance with another feature in an exchange of this type means is provided whereby a testing circuit is adapted to be associated in succession with conversation switches having associated therewith different control circuits, whereby a rapid test of the control circuits may be affected.

According to a further feature in an exchange of the above kind, test circuits are provided for testing the apparatus at each numerical switching stage, such test circuits being provided with means for taking into use in turn each one of a number of the switches used in establishing a connection and for automatically extending a connection thereover to a predetermined test line.

A still further feature consists in the provision of a testing circuit for automatically testing in turn the operation of a plurality of link circuits each comprising a backwardly hunting finder switch and a group selector switch, in which means is provided for controlling the advance of the finder switch of

a link to be tested to a test line which terminates in its bank, and for subsequently exercising control over said test line to cause a connection to be extended over the group selector switch of said link circuit to a further test line extending back to said testing circuit.

These features will be more fully appreciated from the following description of one method of carrying the invention into effect which is given by way of example and should be studied in conjunction with the accompanying drawings. It will be understood, however, that the invention is not limited to the particular arrangement shown and that various other circuit arrangements could be readily devised by those skilled in the art without departing from the scope of the appended claims.

In the following description the invention is described as applied to a system of the kind fully described in our co-pending U. S. application No. 370,673, which used the principle of revertive control of single-motion power driven switches controlled by common control circuits.

It has not been considered necessary to illustrate or describe in detail the operation of the switching apparatus to be tested as this is identical with that described in the specification previously referred to.

Referring now to the accompanying drawings.

Figure 1 shows schematically the layout of a system of the kind referred to and enclosed within the dotted line rectangles, three testing circuits for testing the switching apparatus at the first, second and third switching stages respectively.

Figure 2 shows the testing circuit for testing the second line finder and first group selector link circuits.

Figure 3 shows the testing circuit for testing the second group selectors and their associated control circuits.

Figure 4 shows the testing circuit for testing the final selectors and their associated control circuits.

Referring first to Figure 1, a brief description will be given of the switching appara-

tus involved in an ordinary call between a calling subscriber S and a wanted subscriber S1, followed by a general explanation of the manner in which the testing circuits are used to make the required routine tests.

5 A calling subscriber S is extended over first and second backwardly-hunting line finders 1LF, 2LF to a first group selector finder 1GF having associated therewith an idle control circuit 1CF. Immediately thereafter 10 the link circuit comprising the second line finder 2LF and the group selector 1GF becomes attached to an idle register controller RC over a finder PR whereupon dialling tone 15 is sent to the calling party. Four digits are non-dialled into the register controller RC which thereafter controls the extension of the call of the first group selector 1GF, a second group selector 2GF and a final selector FF, 20 these selectors being operated under the control of common control circuits 1CF, 2CF, FCF which send revertive impulses to the register-controller RC.

The testing circuit T1 is arranged to test 25 100 link circuits such as 2LF—1GF. A test line TL extending from the testing circuit T1 is multiplied in the banks of each line finder 2LF of this group of 100 links and is arranged to be marked as calling in the bank 30 of any one of these finders over a brush of a 100-point switch TF associated with the testing circuit T1. When the test is commenced, the test line TL is marked as calling to the finder 2LF of a link on which a test is to be 35 made, and the finder switches of the group to which the finder to be tested belongs are advanced until this particular finder engages the test line TL. When an idle register-controller RC has become attached to the link 40 under test, an impulse sending switch associated with the testing circuit T1 automatically sends into the register controller RC four digits necessary for extending the call over the first group selector 1GF, a second group selector 2GF and a final selector FF 45 to a test line 1TL which terminates in the final selectors and extends back to the testing circuit T1. By throwing a special key the impulse sending switch in the test circuit may 50 alternatively be caused to stud two digits to the register to direct the connection to a special service group in the second selector 2GF from which a test line STL extends to the test circuit T1. In either case if the apparatus 55 has functioned correctly a relay is operated in the test circuit T1 and the switch TF is advanced to the next second line finder and the test is repeated.

The testing circuit T2 is arranged to test 60 100 second group selectors and their associated control circuits and has associated with it a 100-point switch TGF which has access to these group selectors over three wires in exactly the same manner as a preceding first group selector. A switch is pro-

vided in the testing circuit which simulates the action of a register controller in controlling the extension of a connection to a test line 2TL which terminates in the final selectors and extends back to the control circuit. If the apparatus has functioned correctly the switch TGF is advanced to the next group selector and the test repeated. Provision is made whereby the switch TGF may be successively advanced to group selectors 75 served by different control circuits in order that a rapid test may be made of the control circuits.

The testing circuit T3 is similar to the testing circuit T2 with the exception that it controls two selective operations to extend connection over a final selector picked out by the switch TFF to a third test line 3TL.

In each testing circuit means is provided for advancing the switches TF, TGF, TFF under manual control to test predetermined switches.

A detailed description of the operation of the testing circuit T1 will now be given with reference to Figure 2.

When the start key AK is depressed relay Tr is energized over a circuit, ground, AK4, brush and contact of bank d, of switch TF, Ar2. A circuit AK4—5, Mr1, Sr2, Fr5 is also closed for relay Br which at contacts Br2 holds open the circuit of relay Lr. Relay Tr opens the circuit of the power magnet PF at contacts Tr1, lights a lamp TL to indicate that the test finder TF is arrested on a terminal set, and at contacts Tr2 closes a circuit for relay Cr which extends from ground at springs 2 of key DK, Cr3, AK2, Tr2, AK1, Cr1, winding of Cr to battery. Relay Cr locks up over its make-before break springs Cr1—2, DK1, Mr1, AK5—4, at contacts Cr4 100 closes a circuit for relay Ar, which locks to springs AK4—5 and at contacts Cr6 closes a point in the "b" wire of the test line TL.

A check is now made to determine whether any line finders of the group to which the finder to be tested belongs are rotating. This is effected as follows: Relay Cr at contacts Cr7 connects relay Or via contacts Fr2 and the brush b of the test finder TF and strapped contacts of the arc to the starting circuit of the finder group, and at contacts Cr5 closes a circuit for a slow-acting relay Sr from ground at contacts Or1. If there is a call in the finder group the start relay Csr is energized and the quick acting relay Or energizes over the front contacts of relay Csr and opens the circuit of relay Sr before this relay has time to operate. When relay Csr falls off however relay Or relapses and completes the circuit for relay Sr which locks over Sr1, Mr1, AK5—4 and opens the circuit for relay Br. Relay Lr is now energized over the following circuit,—battery winding of relay Lr, Fr4, Br2, Cr6, contact and brush e of impulse sending switch IF, springs 4 of 125

key EK, Rr1, springs 2 of jack MJ, Er1 to ground. Relay Lr at contacts Lr1 connects a test potential to the test terminal of the finder to be tested via brush *b* and terminal 6 of the test finder TF and at contacts Lr2 closes via brush *c* the circuit of the starting relay Hsr of the group of finders including the finder to be tested. Relay Hsr closes the circuit for the power magnet PL of the 10 finder to be tested and other finders of the group and when this finder engages the test terminal set, relay Er is energized over the *c* wire at contacts Er1 opens the circuit of relay Lr and at contacts Er2 energizes relay Fr.

The relapse of relay Lr opens the start circuit and removes the test potential from the brush *a* of the test finder TF. Relay Fr initiates a test for checking whether a register 20 controller has become attached to the finder under test. Relay Fr at contacts Fr4 connects the winding of relay Br to the starting circuit of the group of register controllers serving the line finder link under test. If a 25 register controller has not been attached relay Br energizes over the front contacts of the start relay Ar and holds open the driving circuit of the impulse sending switch IF until the relays Ar releases. With relay Fr energized and relay Br de-energized, the driving 30 magnet IP of the impulse switch is energized over the following circuit—battery, magnet IP, springs 1 of jack MJ, Ir1, Gr1, Br1, Fr1, Mr1, AK5—4 to ground.

The switch IF is equipped with five brushes. The brush *c* or *e* (according to the operated or non-operated condition of a key EK) is connected via contacts Rr1, MJ2, to the *a* wire of the test line TL and the contacts 40 engaged by these brushes are strapped together and connected to the *b* wire. The contacts engaged by the brush *c* are so spaced that the switch in rotating transmits fast impulses over the loop *a* *b* whilst the contacts engaged by the brush *e* are so spaced 45 that in rotating slow impulses are transmitted over the loop. The contact rows wiped over by brushes *a* and *b* determine the number of impulses transmitted by the switch, the row wiped over by brush *a* being correspondingly spaced to the row engaged by brush *c* which transmits fast impulses, and the row wiped over by the brush *b* being correspondingly spaced to the row engaged by the brush *e* 55 which transmits slow impulses. By means of the strapping terminals XY any pair of contacts in the rows *a*, *b* may be connected to ground over springs 3 of key SK. The ninth contacts are grounded over springs 1 of key 60 SK so that if, as shown, no strapping is provided nine impulses are sent in each rotation of the switch. The tenth terminals are directly grounded for a purpose which will be clear from the subsequent description. In 65 the drawings the fast and slow impulse con-

tacts have for simplicity been shown of equal length and spacing, but it will be understood that in practice the terminals in rows *a* and *c* are shorter and more closely spaced than those in the rows *b* and *e*. Four contacts 1 to 4 provided at the end of the row *d* are used for counting the impulse series as will be described subsequently.

Assuming that the key EK has been thrown for fast impulsing, the brushes *a* and *c* are connected up and impulses are transmitted over the loop by the brush *c*. When nine impulses have been sent relay Dr is energized over the brush *a*, locks up over its contacts Dr2 and the off-normal contacts N and at 70 contacts Dr1, short-circuits the impulsing brush *c* and contacts for the remainder of the rotation. When the brush *d* engages the contact 4 relay Jr is energized, locks over contacts Jr3, and at contacts Jr2 prepares a circuit for relay Ir. On the switch arriving in its normal position relay Dr is unlocked and during the next rotation of the switch a second series of nine impulses is sent and when the brush *d* engages contact 3 relay Ir locks 80 energizes and prepares the circuit of relay Hr. In a similar manner two further impulse series are transmitted during third and fourth rotations of the switch, relays Hr and Gr respectively becoming locked 85 energize at the end of these impulse series. Relay Gr at contacts Gr1 opens the original circuit of the power magnet IP, but the switch IF continues to drive to its normal position the circuit for the magnet IP being 90 maintained over the front contacts of relay Pr which is energized over the off-normal contacts N.

The switch IF normally sends four series of impulses as described above to set up a connection to a test line such as ITL accessible to a final conversation switch. If, however, the key SK is thrown the impulse switch IF is caused to transmit the two series of impulses necessary to complete a connection to 100 a special service test line. The first impulse series corresponds to the digit 0 and the second is determined by a strapping between the terminals X and Y. By throwing the key SK to ground is removed from the ninth contacts in rows *a* and *b* so that ten impulses are sent in the first rotation, relay Dr not being energized until the directly grounded tenth contacts are engaged. The opening of 105 springs 2 of key SK makes the circuit of the magnet IP dependent upon contacts 1 of relay Ir. During the second rotation ground is connected over contacts Jr1 and over a strapping XY to a certain terminal in the contact row *a* or *b* and when at the end of 110 this rotation relay Ir is energized it opens the original circuit for the power magnet IP which however is maintained energized over front contacts of relay Pr until the switch reaches its normal position.

When the impulses have been sent the routine test circuit waits for the completion of the test call. When the test line is seized a slow release relay R_r operates over the backward loop and breaks the forward loop at contacts R_r1 thereby initiating the release of the switches in the connection. If a special service test line is used a further relay similar to relay R_r will be provided having its contacts connected in series with the relay R_r so that the energization of either relay will cause release. When the booster metering current is connected to the c wire relay M_r operates and unlocks all the relays in the routine test circuit with the exception of relay A_r .

When relay Cr relapses a circuit $DK2, Cr3, AK2, Tr1$, is closed for the power magnet PF which drives the switch TF . On the brush d leaving the terminal on which it is standing relay A_r is unlocked and relay Tr is again connected to the contacts in row d and again becomes energized when the brushes are properly centred on the next terminal set. The test now begins again as previously described.

If the routine finder circuit is stopped on a busy second finder, key DK may be depressed to unlock relay Cr . When the key DK is released ground is reconnected to the power magnet PF which drives the switch TF to the next line finder terminals.

For advancing the switch TF to particular second line finder circuits a set of tens keys TK is provided for earthing the first terminals in the tens groups of contacts in the row e of the switch TF and a set of units keys UK is provided for earthing the units contacts in the tens groups in this row. To test a determined second line finder circuit, say that the number of which is 25 in the 100 group serves by the routine test circuit, the tens key $TK21$ and the key CK are first thrown. The key $TK21$ applies ground to the 21st contact in the row e whilst the key CK completes a circuit via $AK3, Tr1$, for the power magnet PF . When the brush e reaches the 21st terminal, relay Tr energizes over brushes e and d , and contacts $Ar2$, locks over contacts $Tr3$ and key CK , lights supervisory lamp TL over contacts $Tr4$, and at contacts $Tr1$ opens the circuit of the magnet PF . The keys $TK21$ and CK are then released. The relay Tr remains energized and holds open the circuit of magnet PF until both keys $TK21, CK$ are restored. The release of key CK opens the original circuit for magnet PF . Keys $UK5$ and CK are next thrown, the circuit for magnet PF is again closed and when the switch TF arrives in position 25, relay Tr energizes as before, arrests the switch TF and lights lamp TL .

The wanted line finder circuit having been reached keys $UK5$ and CK are released and key IK is thrown to start the test. Relay Cr

is energized over springs $IK2$ and locks via $M_r1, 1K1$. The test proceeds as already described and on the energization of relay M_r , relay Cr relapses but no driving circuit is closed to advance the switch TF . When relay M_r de-energizes relay Cr again operates and the test is repeated on the same line finder circuit. The test is repeated in this manner until the key IK is released.

A jack MJ is provided into which the test clerk can plug to check the transmission of dialling tone from the register controller. By plugging into the jack MJ before throwing the key IP the clerk connects his headset across the a and b of the test line TL wires and is able to hear the dial tone. The opening of the springs $MJ1$ and $MJ2$ disconnects the power magnet IP and opens the impulsing loop thereby preventing the operation of the switch IP until the plug is removed from the jack MJ .

The line condition may be changed by the aid of keys GK, HK , and JK through the medium of which a 20000 ohm leak, a 1000 ohm line and an extension set respectively may be introduced on the test line.

The test circuit may be used to test more than 100-line finder links by providing two or more switches such as TF the wires from the brushes of which may be connected to the test circuit over suitable keys.

The operation of the testing circuit shown in Figure 3 will now be described.

Automatic test of conversation group selector finders and common control circuits

The starting key $2AK$ is thrown and provided the test circuit finder TGF is centered on the contacts of a group selector finder the relay $2Tr$ is energized over a circuit, $2AK4, 2Ar2$, brush d of switch TGF and bank contact, $2Ar2$, and completes a circuit for relay $2Br$ over $2Er3, 2Cr2, 2DK2, 2AK1, 2Tr2, 2AK3$, winding of relay $2Br$ and brush c of the switch TGF . Relay $2Br$ operates to the battery applied to the c wire if the group selector and its associated control circuit are free, and closes a circuit for relay $2Cr$ which extends from battery over winding of relay $2Cr$, contacts $2Br1$, home contact and brush of bank e of a control switch $RTS, 2Cr6-7, 2AK5-4$ to ground. Relay $2Cr$ locks up over contacts $2Or3$ and $2Gr1$ in parallel and its make before break contacts $2Cr6$. A lamp $2BL$ is lighted over a parallel circuit to indicate that the switch TGF is centered on the contacts of an idle group selector.

Relay $2Cr$ closes a circuit $2Or1, 2Cr5-4$ for relay $2Ar$ which locks over its contacts $2Ar1$ and disconnects the test relay $2Tr$.

Relay $2Cr$ at contact $2Cr5$ also connects ground via contacts $2Or1$ to the c wire thereby rendering the engaged group finder switch busy, and at contacts $2Cr4$ closes a circuit $2Or1, 2Cr5-4, Nr1, Mr1, Ur5$ for relay Kr .

Relay K_r connects battery to the a wire of the fundamental circuit via contacts $Kr1, Dr1$ and ground to the b wire via contacts $Kr2$, winding of relay $Pr, Dr5, 2Cr3$. The control circuit associated with the group selector finder under test is thereby taken into use as fully described in our U. S. application 370,673 and three selections are made one in the group selector and two in a final selector, the relays $K_r, Mr, Pr, Rr, Nr, Sr, Qr, Dr$ functioning substantially in the same manner as the like-named relays in the register-controller in the application referred to. When the control circuit associated with the group selector becomes attached to the latter, the outstepping relay Pr is energized over the b wire and closes a circuit via contacts $Mr3$ for relay Rr which closes a circuit $Rr2, 2Cr4-5 2Or1$ for relay Nr and at contacts $Rr5$ connects the outstepping relay Pr in a metallic circuit across the a and b wires. Relay Nr opens the circuit of relay Kr .

The group selector control switch now advances its brushes to mark a wanted group of trunks in the bank of the group finder and sends reverte impulses to short-circuit the relay Pr , at each relapse of which a circuit is closed via contacts $Rr3$ for relay Qr , which closes a circuit for the stepping magnet $2Rt$ of the register switch RTS and holds over its contacts $Qr1$ and the interrupter springs of the magnet $2RT$ to maintain the circuit of the magnet, even if relay Pr should open its back contact before the magnet $2RT$ is fully energized.

In the present case it is assumed that the first selection corresponds to the digit 5. The first four contacts in the arc a of the switch RTS are therefore strapped together and jumpered to the contact 2 of relay Ur . The first selection may obviously be varied to meet requirements by changing the strapping of the bank a . When the relay Rr was energized it locked up over its right-hand winding, contacts $Rr4, Vr5, Ur2$ are strapping and brush $a 2Cr4-5$ and $2Or1$.

When the switch RTS arrives in position 5 the holding circuit for relay Rr is opened and on the next relapse of relay Pr the relay Rr relapses, opens the fundamental circuit and deprives relay Nr of current. Relay Nr being of the slow-to-release type remains in its front contact $Nr2$ long enough to cause the energization of relay Sr via contacts $Rr1$. A series circuit is now closed for relays Mr and Qr extending over arc contact and brush b of the switch RTS, $Ur1, Sr1, Nr2$. Relay Qr energizes the magnet $2RT$ of the switch RTS whilst relay Mr at $Mr4$ recloses the fundamental circuit and locks over $Mr2, Pr2$. When relay Sr relapses relay Qr de-energizes and the switch is advanced to position 6 in which relay Ur is energized via $Vr6$ and brush a , locks over contact $Ur3$, connects ground to the first contact in the arc of switch

RTS over contacts $Ur1$, opens the circuit of relay Kr at contacts $Ur5$, and at contacts $Ur4$ closes a restoring circuit for the magnet $2RT$ of the switch RTS. When the brush c engages the first contact in its arc, relay Vr energizes locks over $Vr3$ and unlocks relay Ur which opens the circuit of the magnet $2RT$ and reestablishes the circuit of relay Kr .

During the opening of the fundamental circuit between the relapse of relay Rr and the response of relay Mr , the hunting operation of the group finder is initiated, as fully described in the U. S. application previously referred to.

When relay Kr re-operates it initiates the second selective operation as before, relay Rr being locked up via $Rr4, Vr4$ and contact and brush d of the switch RTS. The switch RTS is stepped as before by reverte signals from the final selector switch. When the switch RTS arrives in position 5 the locking circuit for relay Rr is opened at arc d , the circuit of relay Nr is opened and between the relapse of relays Rr and Nr , relay Sr is energized as before. Before the relapse of relay Nr a circuit $Xr1, brush e, Vr2, Sr1, Nr2$ is closed for relay Qr and when relay Nr falls off the switch RTS is driven to position 6 in which relay Xr is energized over brush c and contacts $Vr3$, locks up over $Xr3$ and prepares a circuit for relay Dr at $Xr2$.

The final control circuit finder is driven in this manner to terminal set number 71 and as the otherwise unused terminal set marked $H1$ in Fig. 9 of the U. S. application referred to is used for test calls eleven steps are required at the final control circuit for units selection. It should be noted that after the tens selection the switch RTS is not restored stepping for the units selection beginning at position 6.

When the relay Rr relapses it opens the fundamental circuit to initiate group selection by the final selector switch and when relay Nr falls back a circuit $Ur5, Mr1, Nr1$, is closed for relay Kr which closes a circuit for relay Pr over the b wire in series with the instepping relay at the final control circuit. The relays Rr, Nr now respond as before the relay Rr reclosing the fundamental loop over the a and b wires.

The switch RTS now makes ten steps in response to reverte signals and in arriving in position 5, relay Rr is unlocked and relay Sr energized. A circuit is then closed for relay Dr (over brush $e, Vr2, Sr1, Nr2$) which locks over $Dr3$ and connects the a and b wires to the windings of relay $2Or$ over contacts $Dr2, Dr4$.

If the final selector switch has tested the correct line $2TL$, relay $2Er$ is energized and when the metallic through connection becomes established relay $2Fr$ and $2Or$ energize in series and a circuit is closed for relay $2Gr$. Relay $2Cr$ is thereby unlocked, closes

a restoring circuit for the switch RTS and opens the locking circuit of all the operated relays except relay 2Ar.

The *a* and *b* wires are now disconnected and the group and final selector switches are released. Relay 2Er relapses and closes a circuit 2Er3, 2Cr2, 2DK2, 2AK1, 2Tr1 for the power magnet 2PF which advances the switch TGF. When the brush *d* leaves the terminal on which it was standing, relay 2Ar relapses and connects up the test relay 2Tr which energizes and arrests the switch TGF when it reaches the next contact set. Lamp 2TL is again lighted and the test is repeated on the next group selector provided it is free.

If the group selector or its control circuit is busy, relay 2Br does not operate and the lamp 2BL does not light. By momentarily depressing key 2DK the relay 2Ar is energized, locks over 2Ar1 and de-energizes relay 2Tr which recloses the driving circuit for the magnet 2PF. When the switch TGF leaves the position in which it is standing relay 2Ar is unlocked and again connects up the test relay 2Tr.

If a final selector in response to a test seizes a line other than the test line 2TL, relay 2Or becomes energized when the called subscriber removes his receiver. As relays 2Fr and 2Er are not energized, relay 2Cr is not de-energized but all the remaining relays except 2Or and 2Ar relapse and relay 2Or remains held over 2Or2, 2Er1. The chain of switches is therefore released and the called subscriber is freed, but due to the fact that relay 2Cr is maintained operated the switch RTS is not restored, and the switch TGF is not advanced. The lamp 2BL remains lighted. A key 2PK is provided which when thrown short-circuits a resistance to vary the line conditions over the fundamental loop circuit.

Rapid test of control circuits

With the key 2EK depressed the test relay 2Tr is only connected to the first terminal of each set of ten terminals in the row *d* of the switch TGF. When therefore the key 2AK is thrown, the switch TGF is arrested on one of these terminals and on the completion of the test the switch TGF is advanced over the nine intermediate positions to the next tenth terminal and tests the control circuit associated with another group of ten group selector finders.

Test of a determined group selector switch

Two sets of keys 2TK and 2UK are provided for grounding respectively the tens and units terminals in the row *e* of the switch TGF. To test group finder number 16 for example, keys 2TK11 and 2CK are operated and a circuit is thereby closed for the magnet 2PF which advances the switch TGF to po-

sition 11 in which the test relay 2TR is operated over key 2TK11 and brushes *e* and *d* to arrest the switch and light a supervisory lamp 2TL. Relay 2Tr is locked over 2Tr3 and key 2CK and releases when both keys 2CK and 2TK11 are restored.

Keys 2UK6 and 2CK are next depressed and the switch TGF is again advanced until relay 2Tr is energized in position 16 and again lights lamp 2TL.

The test clerk now releases keys 2UK6 and 2CK and throws key 21K to start the test which proceeds as already described. On the relapse of relay 2Er however no circuit is provided for the power magnet 2PF of the switch TGF which remains on the same group selector. Relay 2Br however is again energized and recloses the circuit of relay 2Cr which causes the test to be repeated. The test is repeated on the same group selector until key 21K is restored.

The test circuit, Fig. 4 for testing the final selector switches and their associated control circuits operates in substantially the same manner as the circuit shown in Fig. 3 with the exception that the register switch 3RTS is adapted to respond to two series of retractive impulses only.

Automatic test of conversation final selectors and control circuits

When the starting key 3AK is thrown provided the brushes of the switch TFF are properly centred relay 3Tr is energized and if the final selector and its associated control circuit are free, relay 3Br operates and closes a circuit for relay 3Cr via brush *b* of the switch 3RTS. Relay 3Cr locks up over contacts 3Fr2 and 3Or3 in parallel, energizes a relay 3Hr and closes a circuit for relay 3Ar which disconnects relay 3Tr. Relay Kr is also operated and connects battery and earth to the *a* and *b* wires respectively over brushes *a* and *b* of the switch TFF.

The relays Kr, Rr, Sr, Nr, Gr, Pr and Dr function in the same manner as correspondingly-named relays in Fig. 3.

The switch 3RTS is arranged to so control the tens and units selections of the final selector that the latter is directed to a test line 3TL which extends back to the routine test circuit. In the present case it is assumed that this line is reached by making ten steps for the tens selection and eleven steps for the units selection the wipers of the final control finder being directed to the otherwise unused terminal set indicated H in Fig. 9 in the U. S. application referred to. The switch 3RTS is not restored between the two selective operations.

The retractive impulses of the tens selection cause relapses of the relay Pr, as in the arrangement shown in Fig. 3. In position 10 the holding circuit for relay Rr, (over brush *a*) is opened and on the next relapse of

relay P_r the relay R_r falls away and opens the fundamental circuit to send the necessary signal to the final switching stage to commence the unit selection. Between the relapse of relays R_r and N_r , relay S_r is energized and closes a circuit for relay Q_r and on the relapse of relay N_r the switch 3RTS is driven to position 11 in which the relay 3V_r is energized over the brush b , locks up over its inner right-hand contacts and prepares circuits for relays D_r and 3Fr.

On the relapse of relay N_r , relay K_r again energizes and closes a circuit for relay P_r over the b wire of the fundamental circuit in series with the instepping relay at the final control circuit. Relays R_r and N_r now energize again and the fundamental loop is reclosed over a and b wires.

The units selection now takes place, corrective signals causing the switch 3RTS to be stepped to position 10 in which relays R_r and N_r are de-energized and relay S_r is energized as before. Relay D_r operates over brush c , locks up, lights a supervisory lamp CL, and connects the b brush of the switch TFF to the right-hand winding of relay 3Or via contacts D_r , 3Cr3.

Provided that the final selector switch has been advanced to the test line 3TL, relay 3Er is energized over the test wire, and relay 3Xr is energized over the ground connected (over contacts F3r4, Fig. 6 shown in the U. S. application referred to) to the a wire in the final finder switch. Relay 3Xr locks up and its contacts 3Xr3, at contacts 3Xr1 bridges the ringing relay 3J_r and condenser C across the a and b wires, and at contacts 3Xr2 connects the left-hand winding of relay 3Or to the a brush of the switch TFF via contacts D_r 2.

When the relay 3J_r responds to the transmitted ringing current it closes a circuit for a slow release relay 3Gr, which short circuits the winding of slow-release relay 3H_r which relapses and completes the circuit of relay 3Fr which locks up at contacts 3Fr1, at contacts 3Fr2 opens one locking circuit of relay 3Cr and at contacts 3Fr3 bridges an 1100 ohm resistance R2 across the ringing relay 3J_r and condenser C thereby causing the final selector ringing relay to operate and establish the metallic through-connection. If a telephone set has been plugged into the jack LJ the ringing tone can be checked. Relay 3Or is energized over the line, extinguishes the supervisory lamp CL, and releases relay 3Cr which closes a restoring circuit for the switch 3RTS and unlocks all the operated relays in the test circuit except relay 3Ar. The circuit of the power magnet 3PF of the switch TFF is closed over back contacts of relay 3Er so proving that the final selector has been released. Relay 3Ar relapses when the switch TFF advances and relay 3Tr energizes when this switch is correctly centred on the next terminal set. Lamp 2TL is lit and the

test is repeated on the next final finder provided it is free.

The purpose of the slow-release relays 3Gr, 3H_r, 3Fr is to prove that the ringing relay of the final selector under test does not operate over the 8000 ohm resistance R1 which is normally bridged across the relay 3J_r and condenser C. If this happens the metallic through-connection is established before the relapse of relay 3Fr. Relay 3Or energizes, removes the ground from the c brush of the switch TFF and so releases the final selector. Relay 3Er therefore de-energizes and provides a locking circuit for the right-hand winding of relay 3Or. The relay 3Cr remains locked over contacts 3Fr2 and the lamp 3BL remains lighted.

If the final finder under test is incorrectly brought to a free subscriber's line the relays 3Er, 3Gr are not energized but when the called subscriber answers the bridged relay 3Or energizes, releases the final selector and frees the subscriber by removing ground from the c brush of switch TFF. The relays 3Or and 3Cr remain locked up however and the lamp 3BL lighted as described in the previous paragraph. The switch 3RTS does not restore and a new test cannot be started.

A key 3DK is provided for causing the advance of the switch TFF if it stops on the contacts of a busy final selector. The operation is the same as in the arrangement described with reference to Fig. 3.

The line conditions over the fundamental circuit may be varied by means of a key 3PK as in the arrangement shown in Fig. 3.

Test of a determined final finder switch and rapid test of control circuits

These tests may be effected in the same manner as in the circuit described with reference to Fig. 3, the keys 3TK, 3UK, 3EK, 3IK, 3EK controlling the operations in the same manner as correspondingly-named keys in that figure.

Test for busy condition

The response of a final selector to a busy condition may be tested by throwing keys 3BK, 3AK. Key 3BK removes the battery applied over relay 3ER from the third wire of the test line 3TL and substitutes ground, bridges the positive and negative terminals, and connects the left-hand-winding of relay 3Or to the a brush of the switch TFF. As soon as key 3AK is thrown the cycle of operations starts and is completed as described for the automatic test, but when the test line 3TL is seized, the ringing relay 3J_r and the bridge relay 3Or are not operated and relay 3Cr is not released; and the lamp CL remains lighted. A telephone set can be plugged into the listening jack LJ and the busy tone checked. The release of the keys 3BK, 3AK restores the test circuit.

What is claimed is:

1. A telephone system comprising a plurality of selector switches, common control circuits therefor, and a testing arrangement 5 adapted to be associated with any one of said switches said arrangement being adapted to perform automatically a series of operations on one of said switches and a control circuit associated therewith, which operations are 10 similar to those which would occur in the setting up of a connection to a wanted line by means of said switch and said circuit.
2. A telephone system comprising a plurality of selector switches, a plurality of common control circuits each adapted to be associated with any one of said selector switches, and a testing arrangement and means for successively associating said testing arrangement with said selector switches having different control circuits connected thereto 15 whereby routine tests may be automatically carried out.
3. A telephone system comprising a test line, a plurality of numerical selecting stages, a plurality of conversation switches in each stage, common control circuits for said conversation switches, test circuits adapted to test the apparatus at each numerical switching stage, and means associated with said test 20 circuits for taking into use in turn each one of said conversation switches and for automatically extending a connection thereover to said test line.
4. A telephone system comprising a plurality of selector switches, common control circuits adapted to be associated with and to control any one of said switches, a test circuit, a device associated with said test circuit to indicate the operation of circuits and switches 25 which may be associated therewith, and means associated with said testing circuit adapted to operate one of said switches to a predetermined position to cause the operation of said device.
- 45 5. A telephone system comprising, a testing circuit, a plurality of link circuits, each of said circuits comprising a backwardly hunting finder switch and a group selector switch, a first test line, a second test line, means for controlling the advance of said 30 finder switch to said first test line and for subsequently exercising control over said first test line to cause a connection to be extended over said group selector switch to said second test line, said second test line extending back to said testing circuit.
6. A system according to claim 5 wherein said first test line is connected to a contact in the bank of said finder switch, means being provided adapted to apply a calling potential to said first test line and to cause said finder switch to hunt for said first test line.
7. A system according to claim 5 comprising a first test line connected to a contact in the bank of said finder switch, means for applying a calling potential to said first test line and to cause said finder switch to hunt therefor, and means for preventing the application of said potential to said first test line and the operation of said finder switch in the event that another one of said plurality of finder switches is in operation when the test is initiated.
8. A system according to claim 5 comprising an automatic impulse sender adapted to transmit series of impulses for controlling the extension of the connection to said second test line.
9. A telephone system comprising, a testing circuit, a plurality of link circuits, each of said circuits comprising a backwardly hunting finder switch and a group selector switch, a first test line, a second test line, means for controlling the advance of said finder switch to said first test line and for subsequently exercising control over said first test line to cause a connection to be extended over said group selector switch to said second test line, said second test line extending back to said testing circuit, an automatic impulse sender adapted to transmit series of impulses for controlling the extension of the connection to said second line, a registering and controlling mechanism adapted to be associated with a link circuit, and means adapted to delay the transmission of said impulses until said mechanism has been connected to said link.
10. A telephone system comprising a plurality of switching stages, a plurality of conversation switches at each such stage, a test line having a device associated therewith which is adapted to be operated when said line is seized, and a testing circuit comprising operating means under the control of which a connection is adapted to be extended over one of said switches of one of said stages and over one of the switches of a succeeding stage to said test line.
11. A telephone system according to claim 1, having an automatic switch over whose brushes said selector switches are adapted to be tested, and a switching device adapted to be operated on the completion of a successful test to cause the test connection to be broken down and to cause said automatic switch to advance to a succeeding selector switch.
12. In a routine test circuit comprising an automatic switch over whose brushes selector switches are adapted to be tested, and a switching device adapted to be operated on the completion of a successful test to cause the test connection to be broken down and to cause said automatic switch to advance to a succeeding selector switch the combination of means adapted to cause a cessation of the testing operations in the event that said succeeding selector switch is busy.
13. A system according to claim 2 comprising

ing means for subsequently causing the testing operations to be continued.

14. A telephone system comprising a testing arrangement having a switching device, a subscriber's line, a plurality of selectors arranged in selecting stages for making a connection to said line, common control circuits for the selectors belonging to each one of said stages, and means whereby said testing arrangement is adapted to set up a testing circuit to said subscriber's line over said selectors, said switching device being adapted to be operated on the reply of the subscriber to initiate the release of the switches engaged in the connection.

15. A telephone system comprising conversation switches, common control circuits therefor, a testing circuit, a test line adapted to be extended between said switches and said testing circuit, means for associating said testing circuit with said conversation switches in a predetermined order, a signal device in said testing circuit and means adapted to cause the operation of said signal device when a conversation switch associated with said testing circuit is positioned on said test line.

In witness whereof, we hereunto subscribe our names this 2nd day of February, 1930, and 3rd day of February, 1930.

GERALD DEAKIN.
EDOUARD FRUM,

*Legal Administrator of the Estate of Lipa
Polinkowsky, Deceased.*
